**FOREHEAD MOUNTABLE NOVELTY
EYEGLASS DEVICE**

Orben M. Lindley, P.O. Box 3485,
Pensacola, Fla. 32506

Filed June 10, 1971, Ser. No. 152,017

Term of patent 14 years

Int. Cl. D21—01

U.S. Cl. D34—15 A

FIG. 3

FIG. 4

FIG. 1

FIG. 5

FIG. 1 is a front elevation of the novelty device with the eyeglass portion in the down position.

FIG. 2 is a side elevation of the device shown in FIG. 1 with the eyeglass portion in its down position.

FIG. 3 is a perspective view of the device with the eyeglass portion in the down position.

FIG. 4 is a perspective view of the device with the eyeglass portion in the up position.

FIG. 5 is a top plan view of the device with the eyeglass portion in the down position.

The side of the device not shown is the same as the side shown.

I claim:

The ornamental design for a forehead mountable novelty eyeglass device, substantially as shown and described.
